UNITED STATES PATENT OFFICE.

JOHN A. STOOPS, OF FENELTON, PENNSYLVANIA.

SUCKER-ROD ELEVATOR.

No. 839,670.

Specification of Letters Patent.

Patented Dec. 25, 1906.

Application filed May 28, 1906. Serial No. 319,038.

To all whom it may concern:

Be it known that I, JOHN A. STOOPS, of Fenelton, Butler county, Pennsylvania, have invented a new and useful Sucker-Rod Elevator, of which the following is a full, clear, and exact description, reference being had to the accompanying drawings, forming part of this specification, in which—

Figure 1 is a perspective view of a sucker-rod elevator embodying my invention. Fig. 2 is an elevation of a portion of the same with the parts in position to be used as a wrench. Fig. 3 is a section on the line III III of Fig. 2, and Fig. 4 is a fragmentary view showing a modification.

My invention has relation to elevators for sucker-rods, and is designed to provide simple means for preventing the guard-finger which holds the sucker-rod in the hook from being broken by the strains brought to bear upon it by the operation of the elevator, especially when the latter is used as a wrench for screwing and unscrewing the sucker-rods from the blocks; and my invention consists in the novel construction, arrangement, and combination of parts, all substantially as hereinafter described, and pointed out in the appended claims.

In the drawings the numeral 2 designates the shank or stem of the device, which is provided at its upper end with the usual swivel 3 and which is forked at its lower end to receive the pivoted hook 4, having the jaw 5 for engagement with the flange or collar of the sucker-rod, as indicated in dotted lines in Fig. 1. 6 designates a guard-finger for preventing the disengagement of the rod by the hook. Formed on the back edge of the hook is a stop projection 7, which when the hook is moved into the position shown in Fig. 2 is designed to engage the inner wall of a recess 8, formed in the forked end of the shank or stem. This engagement forms a positive stop for the hook when the device is used as a wrench for screwing and unscrewing the sucker-rods, thus entirely relieving the guard-

finger 6 from all strains. Heretofore in the use of devices of this kind great difficulty has been experienced by reason of the breaking of these guard-fingers by reason of the strains thrown upon them, and it has been necessary to make them very heavy for this purpose. By the provision of the projection 7 and recess 8 the guard-finger is relieved entirely of its stop function and may be made of a thin light piece, as shown. Instead of using the depending guard-finger 6 I may use a finger 10, extending inwardly from one of the forks or jaws of the head, as shown in Fig. 4.

What I claim is—

1. A sucker-rod elevator having a head, a hook pivoted therein, and a fixed guard-finger secured to one side of the head and arranged to prevent the disengagement of the hook from the sucker-rod, said hook having a stop projection at its closed edge arranged to engage the head on the opposite side thereof from the guard-finger, and thereby hold the hook out of engagement with the guard-finger; substantially as described.

2. A sucker-rod elevator having a forked head and a hook pivoted within the fork, said hook and head having interfitting stop portions; substantially as described.

3. A sucker-rod elevator having a forked head provided with a guard-finger, a hook pivoted within the fork of the head, and interfitting stop projections on the hook and head arranged to prevent pressure upon the hook of the guard-finger; substantially as described.

4. A sucker-rod elevator having a forked head provided with a recess, and a hook pivoted within the fork of the head and having a projection arranged to enter the recess; substantially as described.

In testimony whereof I have hereunto set my hand.

JOHN A. STOOPS.
